[57] **ABSTRACT**

A one-piece plastic box top for pantry-type food boxes and the like, comprising top, two sides, and two ends, with one entire end pivoted on a unitary hinge to open downward providing complete clearance for contents of a box to be poured without touching the box top, and with the other end of the box top sealed to the sides to position them, assuring a tight fit; means are provided to hold the hinged door in the open position and in the closed position.

UNITARY HINGED PLASTIC PROTECTOR FOR OPENED SHELF-STORAGE TYPE BOXES

This application is related to my copending application for United States Patent entitled BOX-SOX SYSTEM FOR PROTECTING CONTENTS OF OPENED BOXES, Ser. No. 103,522, filed Jan. 4, 1971, now U.S. Pat. No. 3,692,230.

My co-pending application discloses a novel two-part BOX-SOX which is adjustable to fit a variety of sizes so as to seal the contents of opened food packages, and the like, tightly to prevent adulteration, deterioration, or spillage.

The present application provided a top closure for the same purposes which is not adjustable, but which is compensated for by having extremely simplified, efficient structure which can be produced with an absolute minimum of material cost and fabrication. This is a unitary, deep skirt structure with no loose or sliding parts. These features make the novel top closure of this application so suitable for mass production that it can economically be supplied as part of the original package sale of many products such as pancake mixes, cereals, confectioners sugar, and soap products, to name a few already fitted to the package purchased.

In this embodiment the invention is in keeping with present day trends toward bright, attractive household aids which are ever new and clean because they are disposed of and replaced after a short period of use.

In another embodiment the invention is of more permanent nature, so that housewives, restauranteurs, and others can at modest cost purchase at their food stores and supply houses matched sets of the covers which are sized to fit the most often used packages.

The invention is structurally characterized by five flat plates of plastic, four of which are integrally joined at the edges to form a top with downwardly directed sides, and end, and the fifth of which is integrally joined to the top but not the sides, forming a hinged door adapted to close the open end tightly. When the cover is in place on a box having an opening under the door, the door is swung upward, forming a downward opening for dispensing the contents of the box.

Other of the novel advantages and objects of this invention will appear more clearly on examination of the following description taken in conjunction with the drawings.

In the drawings:

FIG. 1 is a perspective of the invention in use, protecting a box;

FIG. 2 is a perspective of the FIG. 1 embodiment, showing the underside; and

FIG. 3 is a plan for a pattern of an alternative embodiment of the invention.

Taking up FIGS. 1 and 2 in detail, FIG. 1 illustrates a box cover 10 made according to principles of the invention, in place protecting the opened upper end E of a box B.

As better shown in FIG. 2, the cover is made up of a top 12, two sides 14, 16, which depend from the top as integral parts, a fixed end closure 18 connecting the sides and top at one end, and a hinged end closure 20 integral with the top 12 along one edge.

The hinged end closure is adapted to engage the adjacent ends 22, 24 of the sides to make effectively sealed joints when the hinged closure is shut. This structure is adapted to cover openings in the upper end of the box E, as well as in the sides and the top itself.

The fixed end 18 braces and holds together one end of the sides, and, when the hinged closure is shut, it braces and holds together the other end of the sides. This arrangement makes a very tight and secure seal on the box, even though the sides may be of thin, flexible plastic. When the end closure is open, the cover is held in place by friction at the fixed end and by the fact that the fixed end is always uppermost when contents are poured from a box protected by the device.

10 A special provision of the invention in the form of recesses 26, 28 in the outer surfaces of the sides which receive respective inwardly protruding flanges 30, 32 on the edges of the end closure, further secures the seal made on closing.

15 The recesses and mating flanges extend substantially the length of the end closure and co-extensive edges of the sides.

20 Material for the device is critical to the extent that the hinge 32 is, for economy and tight sealing, a unitary part of the top and end closure, and for that reason must be flexible. The hinge comprises that part of the structure which lies between that flat top 12, which is braced by the down turned flat sides 14, 16 and the flat end closure 20, which is braced by the flanges 30, 32.

25 Polyethylene is cheap, relatively durable, and can be bent repeatedly, and the device in very economical embodiment can be made of this material.

30 Polypropylene is a more durable plastic, especially adapted to provide almost unlimited numbers of bends at hinge joints.

35 Where the covers are not to be supplied with, and discarded with, the original package protected, the more durable may be preferable.

40 In either case, a matched set in the most commonly used sizes can be packaged and retailed at a low enough price to be very attractive to housewives.

45 It should be noted that not only does this invention intercept dust, liquid spills, and contaminating particles of various kinds which might otherwise enter the tops of opened boxes, but also, the opened-end closure acts as a shield during pouring. Material which may be present on and tend to fall from the top of the closure during pouring is shunted away from the poured contents by the angled face of the opened end closure.

50 FIG. 3, a pattern, shows the design simplicity of cover in which the equality of dimensions is indicated by a, a; b, b and c, c.

55 Although the cover is purposefully ideally adapted for injection molding, an embodiment can be made by stamping out patterns as in FIG. 3, folding on the fold lines, and thermal-welding the two seams between the top and sides.

60 Lastly, an important provision of the invention appears best in FIG. 1. Even though, unlike my prior invention, the present cover is left in place when the contents are poured from boxes, there need be no contact between the food and the cover. There is no cover structure below the opening E, and for this reason plastics which might otherwise be unsuited for this application because of certification problems, can be used, without need for certification.

65 Obviously, many modifications and variations of the present invention are possible in light of the above teachings. It is, therefore, to be understood that within the scope of the appended claims the invention may be practiced otherwise than as specifically described.

What is claimed and desired to be secured by U. S. Letters Patent is:

1. A protector for opened tops of shelf-storage type food boxes and the like, comprising: a unitary structure of flexible plastic material having a flat top, parallel flat sides integrally dependant from opposite edges of the flat top, a fixed flat closure member integral with one end of the top and sides for closing one end of the protector, and a hinged flat closure member integral along the top edge with the other end of the top and adapted for engaging adjacent ends of the parallel flat sides for thereby closing the other end of the protector, said adaptation comprising: the parallel flat sides having means integral with said adjacent ends of the parallel flat sides for sealing against respective edges of the 15

hinged flat closure member, the edges of the parallel flat sides and of the hinged flat closure member being adjacently co-extensive, with said sealing means extending along substantially the entire said ends of the parallel flat sides, and said sealing means comprising exterior faces having recesses along the ends of the parallel flat sides and inwardly protruding flanges on the hinged closure member adapted to engage the said recessed exterior faces of the parallel flat sides.

10 2. A protector as recited in claim 1 wherein said adjacent ends of the parallel flat sides are joined only by said flat top when the hinged flat closure is in the open position, thereby preventing material poured from a said protected box from contacting the protector.
